TELEVISION CABINET

Bernice G. Walent, West Allis, Wis.

Application May 22, 1952, Serial No. 19,819

Term of patent 14 years

(Cl. D56—4)

To all whom it may concern:

Be it known that I, Bernice G. Walent, a citizen of the United States, residing at West Allis, county of Milwaukee, and State of Wisconsin, have invented a new, original, and ornamental Design for a Television Cabinet, of which the following is a specification, reference being had to the accompanying drawing, forming a part hereof, in which:

Fig. 1 is a plan view of a television cabinet, the right side door being open, showing my new design.

Fig. 2 is a front elevational view thereof;

Fig. 3 is a cross sectional view taken on line 3—3 of Fig. 4.

Fig. 4 is a front elevational view with the two center doors in open position.

Fig. 5 is a rear perspective view thereof; and Fig. 6 is a bottom plan view thereof.

I claim:

The ornamental design for a television cabinet, as shown.

BERNICE G. WALENT.
